DESIGN FOR A MIXER FOR BUTTER OR THE LIKE

Ray Swanson, Los Angeles, Calif., assignor of one-third to John L. Wade, Los Angeles, and one-third to William Wirt Lake, Pasadena, Calif.

Application December 23, 1944, Serial No. 117,072

Term of patent 14 years

(Cl. D23—1)

To all whom it may concern:

Be it known that I, Ray Swanson, a citizen of the United States, residing at Los Angeles, in the county of Los Angeles and State of California, have invented a new, original, and ornamental Design for a Mixer for Butter or the like, of which the following is a specification, reference being had to the accompanying drawing, forming part thereof.

Fig. 1 is a perspective view of a mixer for butter or the like, with parts separated, showing my new design;

Fig. 2 is a top plan view;

Fig. 3 is a side elevational view; and

Fig. 4 is a top plan view thereof with the handle and lid shown in Fig. 1 removed.

I claim:

The ornamental design for a mixer for butter or the like, as shown.

RAY SWANSON.
